UNITED STATES PATENT OFFICE.

AXEL M. HOLM AND CARL C. RUSS, OF MOLINE, ILLINOIS.

JAR SEALER.

Application filed April 3, 1924. Serial No. 703,922.

This invention relates to a jar sealer and has for its object to provide a novel device for use in sealing fruit jars or the like.

Another object is to provide a device of this character which is made from one piece of material, is simple in construction and easily manufactured.

A further object is to provide such a device which may be operated solely by pressure exerted through the palm of the hand without the necessity of providing a hold for the fingers.

While we have referred above to fruit jars, it is to be understood that our device is by no means limited to use with such jars but is designed for use wherever similar conditions arise.

In the drawings forming a part of this specification:—

20 Fig. 1 is an elevation of a portion of a jar with our sealer in place thereon.

Fig. 2 is a longitudinal section of our sealer.

25 Fig. 3 is a bottom view thereof, and

Fig. 4 is a plan of a piece of material showing how our sealer may be blanked out therefrom.

It is commonly known that in applying caps to fruit jars and the like a tight seal 30 is made difficult because of irregularities in the flange of the cap or in the glass of the jar and our device is intended to remove such irregularities or to fill them up if they occur in the glass of the jar.

35 Fig. 1 designates a portion of a glass jar of the well known Ball type on which is placed a sealing ring 2 and cap 3, all of conventional design. Usually such cap has irregularities, as exemplified at 4, which prevent a tight seal.

Our improved sealer is designated generally at 5 and comprises a body portion 6 and depending lugs 7. The body is formed to allow a clearance between the same and the top of the jar cap to allow the sealer to be operated freely on the cap without contacting with the cap, to prevent friction at that point. The body 6 is concaved to fit the palm of the hand, Fig. 1, so that an even pressure on the peripheral flange of the jar cap is assured and a clearance between the cap and the body is maintained to prevent friction.

As shown in Fig. 4, the blanks for our sealer may be cut with a great economy of material from one piece 8 of suitable mate-

rial. During this cutting the lugs 7 are cut with their extremities on a curved line which we shall term the peripheral curve. We then provide the extremities of the lugs 7 with curves transversely to the peripheral curves 9, as shown at 10. The outside edges of the lugs are straight as at 11 and the inside edges of the lugs are curved or arc-shaped as at 12 to provide a substantially sharp edge 13 for smoothing or ironing out the jar cap flange and for maintaining a clearance between the outside of the cap edge where it joins the flange and the inside edge of the lugs to eliminate friction at this point. The blanks are then bent into the cup form shown in Figs. 1, 2 and 3, thus completing the finished article. In operation the sealer is held in the palm of the hand and placed in position on the jar, as shown in Fig. 1, the jar resting on any suitable support. It will be obvious that the sealer is supported in position entirely by the depending lugs 7, the body portion 6 of the sealer being disposed above the top of the cap and spaced therefrom. By this means any variation in the vertical height of the cap will not affect the operation of our invention, as there is ample space provided between the inside of the body portion 6 and the extremities of the lugs 7, to receive any of the standard sized caps. Pressure is applied by bearing down with the palm of the hand and a turning movement given to the sealer. The friction between the palm and the top of the sealer is sufficient without any holding means being provided although, if desired, we may roughen the surface. However, we have found such roughening to be entirely unnecessary. Rotation of the sealer will smooth out the irregularities 4, or if irregularities in the glass under the ring 2 are present, the pressure on the sealer will cause the metal of the jar cap 3, which it is well known is soft, to force the rubber of the member 2 into such irregularities in the jar and hold it there. Due to the above mentioned soft character of the metal in the jar cap it will retain the position given it by the sealer and the result is an extremely effective seal for the jar.

It will be seen from the above description that we have provided a jar sealer of extremely simple character, made entirely of one piece, which if made of metal is practically unbreakable and can be very cheaply

manufactured. Furthermore, the sealer can be easily applied, operated by pressure from the palm of the hand only, and easily removed.

5 We are aware that changes in the form, construction and arrangement of parts may be made without departing from the spirit and without sacrificing the advantages of the invention and we reserve the right to 10 make all such changes as fairly fall within the scope of the following claim:—

A jar sealer formed from a single piece of sheet metal comprising, a concave body formed to fit the palm of the hand and

downwardly disposed lugs integrally formed 15 on said body, the outer edges of said lugs being straight and the inner edges being arc-shaped to engage the flange of a jar cap to smooth out any ridges in said cap, said body formed to allow a clearance between 20 said body and the top of the jar cap, said lugs being curved to conform with the shape of the jar cap and spaced therefrom to provide a clearance between the outside of the jar cap and the inside of the lugs.
